UNITED STATES PATENT OFFICE.

CHRISTOPHER P. HINDS, OF CALCITE, COLORADO.

INTERNAL-COMBUSTION ENGINE.

1,114,473.

Specification of Letters Patent. Patented Oct. 20, 1914.

Application filed February 28, 1912. Serial No. 680,379.

To all whom it may concern:

Be it known that I, CHRISTOPHER P. HINDS, a citizen of the United States, and a resident of Calcite, in the county of Fremont and State of Colorado, have invented a new and Improved Internal-Combustion Engine, of which the following is a full, clear, and exact description.

My invention relates to internal combustion engines of the two-cycle type, and it comprises certain improvements in the construction and operation of such engines by means of which fuel forced into the cylinder substantially at the end of the expansion stroke is admitted after the exhaust ports are closed, so as to eliminate loss of fuel by a portion thereof escaping with the exhaust gases; and by means of which fresh air under compression can be forced into the cylinder at the end of the exhaust stroke in such a direction that it will strike the terminals of the igniter and clean it of any soot that may have collected upon the same. This air also serves to flush out the combustion chamber of the engine after the firing stroke and cool the cylinder walls in the usual way.

In its preferred form my invention comprises a cylinder which contains a moving piston having a flange at one end which serves as a pump for taking in and compressing the scavenging air. The body of this piston does not fit the bore of the cylinder snugly, but between the same and the inner surface of the cylinder there is a reciprocating valve sleeve which has a flange at its outer end by means of which gaseous fuel is drawn into the cylinder and compressed and thereafter delivered, through suitable ports in the sleeve and the wall of the piston coming into registry at the proper instant, to the firing chamber of the engine, to be compressed and furnish the power which operates the engine.

The primary object of my invention is to produce an engine of the kind described which will be exceedingly simple, containing but few working parts to wear or get out of order, and which will be smooth and noiseless in operation, providing ample room for the water jacket for cooling the same

and being only a little larger than the average size two and four-cycle engines for automobiles and similar purposes now in common use.

Reference is to be had to the accompanying drawings forming a part of this specification, in which the same characters of reference indicate the same parts in all the views.

Figure 1 is a vertical longitudinal sectional view taken through my improved engine, showing the interior construction thereof and the arrangement of the valve ports for the same; Fig. 2 is a vertical sectional view on the line 2—2 of Fig. 1; Fig. 3 is a horizontal sectional view on the line 3—3 of Fig. 1; Fig. 4 is a view similar to Fig. 1, showing the position of the piston at the beginning of the out stroke thereof; Fig. 5 is a similar view, showing the parts in the position they occupy when the exhaust begins; Fig. 6 is a similar view showing the position of the parts before the exhausting is completed and at the instant when scavenging air enters the cylinder; Fig. 7 is a similar view, showing the position of the parts when the operation of exhausting and scavenging is completed; Fig. 8 is a similar view, showing the position of the parts at the instant when the inflow of the explosive charge begins; Fig. 9 is a similar view showing the position of the parts at the middle of the operation of taking in an explosive charge; and Fig. 10 is a similar view, showing the position of the parts when the inflow of the fuel is completed and the operation of completing the compression of the charge has begun.

On the drawings, the numeral 1 represents the cylinder of the engine which is provided at one end with a crank case 2. The crank shaft 3 projects through the sides of the crank case, being supported in bearings 4, and it carries a crank 5 having a wrist-pin 6 pivotally connected by means of a rod 7 to a cross-pin 8 mounted in the outer end of the body of the piston 9. The piston is hollow, as shown, being closed at one end adjacent the cross-pin 8, and open at its opposite end to receive a boss 10 projecting from the inner face of the cylinder head 11. This

boss 10 may be hollow, as shown, and has an aperture through which projects the igniter 12. The inner surface of the piston 9 fits the curved surface of the boss 10 snugly, and the power chamber of the engine will be the space inclosed by the piston and the end of the boss 10, as will be readily understood.

As will be apparent from the drawings, the outside diameter of the piston is less than the inside diameter of the cylinder, and the end of the piston adjacent the head 11 carries a flange 13 which contacts with the inner wall of the cylinder and serves as a pumping device for drawing in and compressing air that is used in scavenging and cooling the power chamber.

14 represents conduits passing through the walls of the cylinder adjacent the head 11, to permit air to flow freely into and out 20 of the space between the flange 13 and the head 11 when the piston reciprocates; and 15 represents ports which are preferably four in number arranged at intervals of 90° apart to establish communication between 25 the interior of the body of the piston and the space between the piston and the inner wall of the cylinder 1. The scavenging air which enters the space between the piston and the interior surface of the cylinder 30 passes through these openings 15 into the power chamber after the operation of exhausting has begun. The piston 9 is also provided with a pair of ports 16 arranged at diametrically opposite points at the closed 35 end thereof to allow the burned gases to flow out of the power chamber; and these ports are controlled by means of a reciprocating valve sleeve 17, which surrounds the body of the piston and derives its motion from 40 the crank shaft 3. The connection of this valve sleeve through the crank shaft comprises a pair of bolts or pins 18 secured inside of the sleeve 17 at its outer end and serving as journals for a pair of eccentric 45 rods 19 terminating in eccentric straps 20. These straps encircle eccentrics 21, which form part of the crank 5, and by means of these eccentrics the valve sleeve 17 is reciprocated to control the outflow to the 50 burned gases and the inflow of fresh fuel at the proper time in the cycle of operation of the engine.

The sleeve 17 fits the piston 9 snugly, and the outside diameter of the sleeve is less 55 than the inside diameter of the cylinder 1. The sleeve 17 has ports 22 extending through its wall, these ports being diametrically opposite each other and arranged to come into registry with the ports 16 at the proper instant; and on the end of the sleeve 17 which is nearest the crank shaft 3 I form a flange 23, which contacts with the inner surface of the cylinder wall, and acts as a sort of pumping device in a manner similar to the 60 flange 13 on the piston 9.

Between the outer surface of the sleeve 17 and the inner surface of the cylinder 1 is a water jacket 24, to which cooling liquid is supplied by a suitable arrangement of piping, as will be readily understood by those skilled in the art. The upper end of the water jacket, taking the engine in the position shown in the drawings, forms with the space between the same and the inner wall of the cylinder 1 and the piston and flange 70 13 thereon, an air compressing space within which the scavenging air is compressed; and the lower end of the water jacket forms a shoulder between which and the flange 23 on the lower end of the sleeve 17 the gaseous 75 fuel is compressed previous to its entrance into the power chamber to be compressed between the end of the piston and the end of the boss 10.

The numerals 25 represent ports through 80 the wall of the cylinder 1 adjacent the head 11, and the numerals 26 represent exhaust conduits passing through the cylinder walls and the water jackets in proper position to conduct away the burned gases when the firing stroke of the piston is finished.

27 represents an intake valve casing secured to the side of the cylinder by means of a flange 28; and 29 is the intake conduit connected thereto. This valve casing is 85 hollow, containing a partition 30 which is apertured to form a valve seat for a valve 31, the stem of this valve extending outside of the casing and being surrounded by a compression spring 32, which normally acts 90 to hold the valve to its seat.

The space inside the valve casing 27 on the low pressure side of the valve 31 communicates by means of a port 33 through the wall of the cylinder 1 with a space between 105 the flange 23 and the adjacent end of the water jacket 24. From this space lead conduits 34, which terminate in ports 35, through which the gaseous fuel after being compressed is forced into the power chamber 110 of the engine.

The manner of operation of my improved internal combustion engine is as follows: Referring to Fig. 4, the parts are shown in such position that both the sleeve 17 and the piston 9 are moving outward. The flange 13 has just overrun the ports 25, and the ports 15 in the piston 9 have not cleared the inner end of the boss 10. Air which is trapped between the flange 13 and the water 120 jacket 24 is now being compressed. Further, the ports 16 and 22 in the piston and valve sleeve 17 respectively have not yet established communication between the power chamber and the exhaust conduit 26, 125 so that the gases which are at this moment in process of combustion in the power chamber are forcing the piston to move outward and transmit power to the crank shaft of the engine. The movement of the sleeve 17, 130

at this time in the same direction as the piston 9 causes the flange 23 to draw in fuel through the valve 31 into the space between this flange and the adjacent end of the water jacket, to be compressed later. The next step in the operation of the engine is illustrated by Fig. 5. The piston 9 and the sleeve 17 are still moving outward. The ports 15 have not yet overrun the inner end 10 of the projection 10, but the ports 16 and 22 have established communication with the power chamber and the exhaust conduit 26. The burned gases now flow out through the exhaust conduit 26 and the operation of ex- 15 hausting has commenced. When the parts have reached the position shown in Fig. 6, the piston 9 is still moving outward, but the valve sleeve 17 has reached the limit of its out stroke and is about to move inward. 20 The ports 15 in the wall of the piston 9 have cleared the inner end of the projection 10 and the ports 16 and 22 are still in position to provide communication between the exhaust conduit 26 and the power chamber. 25 As a result, the air which the flange 13 has compressed on the power stroke of the piston now flows into the power chamber, passes through the length thereof and blows any burned gases remaining therein out through 30 the exhaust conduits 26, as shown by the arrows.

Referring to Fig. 7, the valve sleeve 17 is shown as having begun its inward stroke, and the piston 9 as having reached the end 35 of its out stroke and being about to start on its in stroke. In this position the ports 22 in the sleeve are out of registry with the ports 16, but still in registry with the ports 26. As a result, the power chamber is now 40 closed. The space between the end of the flange 13 and the adjacent end of the water jacket is still in communication with the power chamber inside of the piston through the ports 15, as shown, and the valve 31 has 45 been closed by its spring, owing to the fact that the flange 23 on the sleeve 17 has begun to put the gaseous fuel trapped between the flange 23 and the adjacent end of the water jacket 24 under compression.

50 Note is to be taken here of the fact that after the ports 16 and 22 in the piston and the valve sleeve have passed out of registry to interrupt communication between the power chamber and the exhaust conduit, communication still exists for a brief inter- 55 val between the power chamber and the space between the flange 13 and the adjacent end of the water jacket 24. As a result, the initial portion of the in stroke of the piston has 60 the effect of rarefying to some slight extent the air in the power chamber. This is be- cause the space occupied by the volume of air inside the power chamber and between the flange 13 and the adjacent end of the 65 water jacket 24, increases to a slight extent

when the flange 13 moves away from the water jacket 24, the parts being designed so that the increase in the space between the flange and the water jacket more than offsets the decrease due to the approach of the 70 closed end of the piston to the inner end of the boss 10.

The next step in the operation is illus- 75 trated in Fig. 8. Both the piston 9 and the sleeve 17 are now moving away from the crank shaft. The ports 15 have come to such position as to be closed by the cylindrical surface of the projection 10, and the ports 16 and 22 have come into position to establish communication to the power chamber through the ports 35. The compressed gaseous fuel trapped between the flange 23 and the adjacent end of the water jacket 24 is now forced through the passages 34 into the power chamber, and this action takes 80 place so much quicker by reason of the fact that the air entrapped in the power chamber has been rarefied, as above described.

Fig. 9 shows the operation of taking in 85 fresh fuel in full swing. Both the piston 9 and the valve sleeve move toward the head 11 of the cylinder on this view, and the ports 16, 22 and 35 are in full registry with one another.

The final step in the cycle of the engine is 90 shown in Fig. 10. In this view the valve 17 has reached the end of its in stroke, but the piston 9 is still moving toward the head 11, and the ports 16, 22 and 35 are no longer in 95 registry with each other. For the remainder 100 of its in stroke the piston now compresses the gaseous fuel against the inner end of the boss 10, and when the igniter 12 is operated, this gaseous fuel is fired and the power 105 stroke of the engine follows. In the course of the engine cycle air will be drawn in through the ports 25 to the space between the cylinder head 11 and the flange 13, when the flange 13 passes these ports when the piston is making its out stroke. On the in 110 stroke of the piston the air drawn in through the ports 25 will be forced out again until the flange 13 passes the same. The air trapped between the flange 13 and the cylinder head may be forced out through the conduits 14 and stored in a reservoir or used to 115 inflate automobile tires, or employed in any other desirable way.

From the above description it will be apparent that I have produced a two-cycle engine in which the efficiency is increased and the construction and operation considerably improved. No fuel can be lost when the discharge of the gases is taking place, a thing which often happens in two-cycle engines of 120 ordinary design, because, in my engine, scavenging air enters the firing chamber and blows out the products of combustion, and then communication with the exhaust conduit is interrupted before the gaseous fuel 125 130

is admitted to the power chamber. This manner of operation has an additional advantage of getting all of the exhaust gases out of the way before the gaseous fuel enters, and thus eliminates the danger of backfiring.

Scavenging air forced into the chamber by the flange 13 blows across the spark points, as shown in Fig. 6, cools the inner surface of 10 the piston and then passes out through the exhaust conduit to complete the scavenging operation.

There is ample room for a water jacket of sufficient size to cool the engine, and the 15 presence of this water jacket does not increase the size of the cylinder. Further, there are but few working parts to wear or get out of order, and this makes the operation of assembling and timing the parts 20 capable of ready and easy accomplishment.

The working of the engine will be smooth and noiseless; it will not be clumsy or bulky, but in fact it need be only a little larger than the average size two and four-cycle engines of the same power now in use for motive power purposes.

Any convenient arrangement of ports through the walls of the piston and the sleeve can be adopted. I have shown two fuel inlet 30 ports through the sleeve and piston located at opposite points, each of these ports serving for both the intake and discharge of gas, discharging the gas when the piston reaches the end of its out stroke, and admitting fuel 35 when the operation of exhausting and scavenging is finished. However, I may use a single outlet port and a separate inlet port in the piston and sleeve if desired, placing the inlet port in the piston and sleeve on one 40 side of the engine and the outlet port in the piston and sleeve on the other side; or I may place both the inlet and outlet ports on the same side, according as circumstances may require.

45 I wish to have it understood that the above description and drawings accompanying the same are illustrative only, disclosing but one embodiment of my invention, and that I do not wish to be limited to the details 50 thereof, but wish to reserve to myself the right to make whatever changes in the shape, size and arrangement of the parts fairly fall within the scope and spirit of the appended claims.

55 Having thus described my invention, I claim as new and desire to secure by Letters Patent:

1. In an internal combustion engine, the combination of a casing inclosing a power 60 chamber, a piston movable in said casing, a flange carried by said piston, said casing having ports through the wall thereof, to admit air to one side of said flange, whereby the movement of the piston will compress 65 said air, means carried by the casing for

conducting the gases of combustion from the power chamber, means also carried by the casing for admitting gaseous fuel to the power chamber, the piston having means for permitting the admission of compressed air 70 to the power chamber after the beginning of the exhaust, and means for controlling the passage of gas to and from the power chamber, so as to admit gaseous fuel to the power chamber after the operation of exhausting and scavenging is finished.

2. In an internal combustion engine, the combination of a casing inclosing a power chamber, a piston movable in said casing, said piston having a flange thereon and said casing having openings admitting air into the same, on one side of said flange, to be compressed upon the movement of the piston, means carried by the casing for conducting away the gases of combustion from 85 the power chamber, means also carried by the casing for conducting gaseous fuel to the power chamber, and means movable with respect to the casing for establishing communication between the power chamber and the means for conducting away the gases of combustion at the end of the power stroke of the piston, said piston permitting the admission of air compressed by the flange thereon into the power chamber after the 90 operation of exhausting has begun to clean out the power chamber, said movable means serving to interrupt communication between the power chamber and the means for conducting the gases away from the same and 100 to establish communication between the power chamber and the means for supplying gaseous fuel thereto after the operation of exhausting and scavenging is finished.

3. In an internal combustion engine, the combination of a casing inclosing a power chamber, and having means for admitting air to a space above the power chamber, a piston movable in said casing, means for compressing a volume of air in the said 105 space, an igniter carried by said casing and projecting into the power chamber thereof, said piston having means for admitting said compressed air to the power chamber at the end of its power stroke, at a plurality of points adjacent said igniter to clean the terminals thereof, and a sleeve valve in the casing and fitting snugly the piston, said valve controlling the outflow of the burnt 110 gases and the inflow of the feed.

4. In an internal combustion engine, the combination of a casing having openings therein, a power chamber inclosed in the casing and spaced therefrom, an igniter projecting into said power chamber, a piston 115 movable in said casing, means operated by said piston for compressing a volume of air in the said space by the piston, said piston having a plurality of ports therethrough, to admit air to said power chamber at the inner 120 130

end of the igniter at the end of the power stroke to cleanse the terminal of said igniter, and a reciprocating sleeve valve in the casing and fitting snugly the piston, said valve controlling the outflow of the burnt gases and the inflow of the fuel.

5. An internal combustion engine comprising a casing, said casing having a plurality of apertures through its wall adjacent the head thereof, an internally-projecting boss carried by the head, a hollow piston mounted in said casing, having an open end receiving said boss, the end of said boss and the interior surface of the piston forming 10 a power chamber, a flange carried by the piston, the outer surface of the body of the piston being spaced from the inner surface of the casing, to provide a space to contain 15 air admitted through said apertures, said air being compressed by the flange upon the movement of the piston, means forming a water jacket located inside the casing and surrounding the piston, forming one end 20 of said air compression space, said piston having a port in its wall, which overruns the end of the boss at the end of the power stroke of the piston, to permit air compressed by the flange to enter the power chamber at the end of the power stroke, and 25 30 a sleeve valve between the water jacket and piston, said valve controlling the outflow of the burnt gases and the inflow of the fuel.

6. An internal combustion engine, comprising a casing having a head carrying an internally-projecting boss, a hollow piston having an open end receiving said boss, the inside of said piston forming with the inner end of said boss a power chamber, means carried by the casing for conducting the 35 40 gases of combustion away from the power chamber, said piston having a port to permit the exhaust of the said gases from the power chamber, and a movable valve sleeve having a port therethrough which establishes communication between the means for conducting away the exhaust gases and the port formed in the piston, at the end of the power stroke.

7. In an internal combustion engine, the combination of a casing having a head thereon, said head having an internally-projecting boss, a hollow piston having an open end receiving said boss, the inside of said piston forming with said boss a power chamber, 50 55 said piston having a port through its wall, means carried by the casing to conduct gaseous fuel to said power chamber, and a movable valve sleeve having an aperture therethrough to establish communication between said conducting means and the port carried by the piston, to admit fuel to said power chamber.

8. An internal combustion engine comprising a casing having a head with an internally-projecting boss thereon, a piston hav-

ing an open end receiving said boss, the inside of said piston forming with the end of the boss a power chamber, said piston having ports through its wall establishing communication with the power chamber, means 70 carried by the casing for conducting away gases of combustion from the power chamber, means also carried by said casing for supplying gaseous fuel to the power chamber, and a movable sleeve having an aperture therethrough which establishes communication between the power chamber and the means for conducting gases therefrom through a port in the piston to exhaust the engine, and which subsequently establishes communication with the power chamber and the fuel-conducting means through a port formed in the piston to supply fuel to said power chamber.

9. An internal combustion engine comprising a casing having a head with an internally-projecting boss thereon, a hollow piston having an open end receiving said boss, the inside of said piston forming with said boss a power chamber, said piston having a port through its wall communicating with said power chamber, a water jacket carried inside of said casing and surrounding the piston, and a movable valve sleeve located between said piston and said water jacket and having a flange at one end and a port communicating with a space between the flange and one end of said water jacket, to admit gaseous fuel, said flange serving to compress said fuel, the port formed in the 100 sleeve being for registry with the port in the piston, to admit compressed fuel to the power chamber.

10. An internal combustion engine comprising a casing having a head with an internally-projecting boss formed thereon, a piston movable in said casing and having an open end receiving said boss, the inside of said piston forming with said boss a power chamber, a water chamber carried inside of the casing and surrounding the piston, a valve sleeve located between the piston and the water jacket, and a flange carried upon one end of the valve sleeve, said flange forming a fuel-compression space between the same and one end of the water jacket, the said casing having a port therein to admit gaseous fuel to said compression space, the said water jacket having a conduit leading from said compression space 110 and terminating in a port leading through the inside surface thereof, and the said piston and said sleeve having ports which come into registry with each other and with the port forming the end of said conduit, to admit gaseous fuel to the power chamber.

11. In an internal combustion engine, the combination of a casing having a head with an internally-projecting boss formed thereon, a hollow piston having an open end re-

ceiving said boss, the inside of said piston forming with the end of said boss a power chamber, said piston being spaced from the inner wall of the casing and having a flange formed thereon, said casing having an aperture to admit air in front of said flange to be compressed thereby and said piston having an aperture therethrough which overruns the end of the boss to admit compressed air to the power chamber, a water jacket carried inside the casing and surrounding the piston, a movable valve sleeve located between the piston and the water jacket, said valve sleeve having a flange at one end and said casing having a port to admit gaseous fuel between one end of said jacket and said flange, to be compressed by the flange, means carried by the casing to conduct the gases of combustion from said power chamber, said piston having an additional port therein and said valve sleeve having an aperture therethrough which registers with the additional port in the piston and the means for conducting the exhaust gases from the power chamber, and means for controlling the movements of the valve sleeve with reference to the piston, to cause the port in the valve sleeve to establish communication between the power chamber and the means to conduct away the gases of combustion when the piston has finished its power stroke, and subsequently, to establish communication between the additional port in the piston and the fuel-compression space, to admit fuel to the power chamber, the air port in the piston admitting scavenging air to the power chamber to flush out the same after the exhaust has begun and before the gaseous fuel is allowed to enter the power chamber.

40 12. An internal combustion engine, comprising a casing having a piston therein, a flange carried by the piston, said casing having an aperture therein to admit air into the same between the inner surface of the casing and the piston, said air being compressed by the said flange, said piston having means for admitting said compressed air to the power chamber at the end of the power stroke, to flush out the products of combustion, and 45 movable means for admitting gaseous fuel to the power chamber after the operation of exhausting has been finished and the piston has begun to move in the opposite direction, the return movement of said piston causing 50 the flange to effect a slight rarefaction of the vapors in the power chamber, to facilitate the admission of the fuel thereto.

13. In an internal combustion engine, the combination of a casing, a movable member 55 therein, said casing having a port at one end of the same and a second port spaced therefrom, and means for operating the movable member to cause the same to close the first port and overrun the second port, whereby 60 air taken into the casing through the second

port on one side of the movable member will be compressed by the same, and air taken into the casing through the said second port on the other side of the member will be forced out through the first port. 7

14. In an internal combustion engine, the combination of a casing having a water jacket, said jacket forming an internal shoulder, a hollow piston movable in said casing and having a flange, said casing having means for admitting air between the said flange and said shoulder to be compressed by the flange, and said piston having a port to allow of the passage of the compressed air into the firing chamber when the said port is uncovered, and a combined valve and pumping device having a portion working between the water jacket and piston, said device controlling the outflow of the burnt gases and the inflow of the fuel. 8

15. In an internal combustion engine, the combination of a casing having a water jacket forming an internal shoulder, a valve sleeve having a flange, means for supplying fluid to the space between the flange and the shoulder to be compressed by the flange, said jacket having a passage and said valve sleeve having a port to register therewith, a hollow piston carried by the casing inclosed by the valve sleeve and having a port to communicate with the port in the valve sleeve, and means for operating said piston and said valve sleeve to supply fluid to the interior of the piston at the end of the power stroke.

16. In an internal combustion engine, the combination of a casing having means for forming an outlet conduit, a piston means for supplying compressed air to the power chamber at the end of the out stroke of the piston to scavenge the same, and means for operating said air-supplying means to withdraw part of said air and create a partial vacuum in the power chamber immediately prior to the admission of the fuel charge, said engine having means for then admitting the charge.

17. In an internal combustion engine, the combination of a casing, a hollow piston inclosing a power chamber, said piston having a port in its wall, means for uncovering said port, means operated by the piston to supply compressed air through the piston port to scavenge the chamber, said means withdrawing part of said air to create a partial vacuum in the chamber prior to the admission of the fuel charge, said engine having means for then admitting the charge.

18. In an internal combustion engine, the combination of a casing, a hollow piston moving in said casing and forming a power chamber, said piston having a port in its wall, means for uncovering said port at the end of the out stroke of the piston, a flange carried by the piston to compress air to be

supplied to the chamber through the port when the same is uncovered, said flange operating to withdraw part of said air and create a partial vacuum in the chamber prior to the admission of the fuel charge, said engine having means for then admitting the charge.

In testimony whereof I have signed my name to this specification in the presence of two subscribing witnesses.
